DESIGN FOR A DRESS

Malvina Wolff, New York, N. Y.

Application September 16, 1940, Serial No. 95,086

Term of patent 3½ years

To all whom it may concern:

Be it known that I, Malvina Wolff, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and
Fig. 2 is the rear view thereof.

I claim:

The ornamental design for a dress, substantially as shown.

MALVINA WOLFF.
